ANTENNA

Henry J. Riblet, Cambridge, Mass., assignor, by
mesne assignments, to the United States of
America, as represented by the Secretary of
War

Application August 1, 1945, Serial No. 608,295

4 Claims. (Cl. 250—33)

1

This invention relates to antennae and more particularly to antennae adapted for use at ultra-high radio frequencies.

It is one object of the invention to build an antenna which will radiate a concentration of energy substantially in one plane.

Another object of the invention is to build an antenna which will have a radiation pattern substantially restricted to the horizontal plane.

A further object of the invention is to construct an antenna which has a radiation pattern substantially non-directional, particularly in the horizontal plane and generally in any plane parallel to the horizontal plane.

Another object of the invention is to build an antenna possessing the radiation characteristics described above which is disk shaped, with the axis of the disk in the vertical plane when radiation is horizontally directed.

Another object of the invention is to build an antenna which makes effective use of material refractive to electromagnetic waves.

Other objects, advantages, and novel features of the invention will appear more fully in the description contained herein.

In the drawings:

Fig. 1 is a sectional view of one embodiment of the invention;

Fig. 2 is a cross-section view of the embodiment illustrated in Fig. 1;

Fig. 3 is a sectional view of a second embodiment of the invention;

Fig. 4 is a sectional view of a third embodiment of the invention; and

Fig. 5 is a top plan view of the structure illustrated in Fig. 4.

Referring now to Figs. 1 and 2, a material refractive to electromagnetic radiation, that is a substance having an index of refraction considerably greater than one, say of the order of 1.6, is formed in a shape such as that of disk 10.

A preferred substance for use in the manufacture of disk 10 is polystyrene, because of its low dielectric losses, but any substance having the desired refractive characteristics such as styramic, hard rubber, acetate butyrate or similar substances may be used. Disk 10 may be described as having substantially the form of a volume of revolution obtained by rotating the surface enclosed by curves 11 and 12 and axis 13 about axis 13. The customary way of orienting the antenna of the type herein described is with axis 13 vertical, and therefore, axis 13 will be termed the vertical axis herein although it will be understood that this is not intended to limit the invention.

Curves 11 and 12 are preferably logarithmic and symmetrical and furthermore, preferably extend out from axis 13 several free-space wave lengths at the contemplated operating frequency.

2

In its preferred embodiment, disk 10 is thus formed symmetrically on each side of the horizontal plane (a plane perpendicular to axis 13) and has a raised or protruding center, the sides extending outward therefrom in concave fashion. Disk 10 is preferably much smaller in thickness through the center than in diameter, a ratio of about 10 to one being satisfactory. Larger ratios will provide stronger directive effects and, conversely, smaller ratios will provide less directive effects. However, the size of disk 10 will affect dielectric losses.

Disk 10 may be molded or cast around an enclosed transmission line 14 and dipole assembly 15, which may be a hollow pipe wave guide or a coaxial type line which enters disk 10 along axis 13. By the construction just described, a source of radiation is provided already possessing in part the desired directive properties. In addition, by molding or casting disk 10 tightly about the assembly, it is thereby well supported physically and provides a weather proof covering for the radiating elements. If the structure is subjected to unusual stress, additional external supporting members may be furnished. Dipole array 15 preferably is constructed of three arcuately shaped dipoles symmetrically arranged about line 14 as described more fully in the copending application of Henry J. Riblet, Serial No. 532,793, filed April 26, 1944.

A study of the disk and dipole array of Figs. 1 and 2 discloses substantial symmetry about vertical axis 13 so that a radiation pattern of the antenna in the horizontal plane, or any plane parallel thereto, is substantially non-directional in character. However, the radiation pattern in any vertical plane, that is any plane including axis 13, shows high intensity of radiation along the horizontal axis and low intensity vertically, either up or down. Visualized in such a vertical plane, the radiation pattern would appear as two similar elongated lobes extending along the horizontal axis. This is due not only to the radiation pattern of the dipole assembly 15, but to the superimposed directive effect of disk 10 which itself would have a radiation pattern of the desired type, even though a source centrally located within it were entirely non-directional in character.

Another modification of the invention is illustrated in Fig. 3. Energy is brought to the antenna array by a coaxial transmission line 16, having a central conductor 17 and an outer conductor 18. The outer conductor 18 contacts a metallic plate 19 which extends normally to axis 20. A probe 21, which is a continuation of inner conductor 17, passes through plate 19 without making electrical contact therewith and is terminated at a second circular plate 22 similar in size to plate 19. Disk 23 constructed of material

refractive to electromagnetic radiation extends outwardly from plates 19 and 22 and may be continued between the plates.

Plates 19 and 22 have the effect of a circular parallel plate wave guide of finite extent centrally excited which produces a radiation pattern similar to that for dipole array 15 except that the radiation is vertically polarized. Again, disk 23 of refractive material increases the directive effect of radiation from the antenna and provides a highly directive radiation characteristic for the combination.

Figs. 4 and 5 illustrate another embodiment of the invention. The external conductor 24 of coaxial transmission line 25 contacts a lower metallic plate 26, extending outwardly from vertical axis 27. Probe 29 is a continuation of the inner conductor 28 of line 25, and reaches to the center of plate 30 which extends outwardly from axis 27. In the preferred embodiment, plates 26 and 30, if continued outwardly from axis 27, would join at a small angle so that they do not extend normally from axis 17. The space between plates 26 and 30 is preferably filled with some material refractive to electromagnetic radiation and an annular filler 31 of material absorbent to electromagnetic radiation may be inserted near the periphery of the plates. Slits 32 and 33 are cut in plates 26 and 30 respectively, preferably arcuate in shape and substantially concentric with, or coaxial with, axis 27. As radiation emanates from exciting probe 29, it will leak through the slits 32 and 33 in plates 26 and 30. The slits are preferably aligned and spaced outwardly in such manner that as radiation progresses through the outer atmosphere after having leaked through one of slits 33, it will be substantially in phase with radiation from the next outwardly located slit 33. A like spacing is observed for slits 32. By this means the radiation emanating from the antenna assembly illustrated in Figs. 4 and 5 is given a sharply directive effect in the vertical plane. Due to the general symmetry of the structure about the vertical axis, radiation will be generally non-directive in the horizontal plane, or any plane parallel thereto.

Although the description herein with regard to the embodiments illustrated has been confined generally to consideration of radiation therefrom, like directive effects will be experienced when the antennae are used for reception, as is well known in the art. Therefore, it is not desired to restrict the invention by the discussion of such radiation effects. Furthermore, for the sake of simplicity, no impedance matching devices have been illustrated in the drawings in combination with the invention. Such devices might consist of adjustable, or adjusted stubs,

plungers, windows, or any of the other well known devices utilized generally for that purpose.

Numerous variations will be apparent to those skilled in the art. Therefore, it is not desired to restrict the scope of the claims to the precise embodiments herein disclosed.

What is claimed is:

1. In an antenna, the combination of an enclosed transmission line, an array of dipoles aligned substantially coaxially around said line and adapted to be excited by energy therefrom, and a disk of material refractive to electromagnetic radiation supported by said transmission line and enclosing substantially coaxially and symmetrically said dipole array, the thickness of said disc diminishing from the center to the edge.
- 10 2. In an antenna, the combination of an enclosed transmission line, a probe adapted to be electrically excited from said transmission line, two metallic substantially plane circular plates forming a wave guide for energy radiated from said probe, a disk of material refractive to electromagnetic radiation enclosing said probe, the faces of said disk being at least partially enclosed by said plates, said plates, said disk, and said probe being substantially coaxial.
- 15 3. In an antenna, the combination of an enclosed transmission line, a probe adapted to be excited by said transmission line, a disk of material refractive to electromagnetic radiation enclosing said probe coaxially, two circular converging plates substantially enclosing said disk and having slits spaced and arranged so that radiation leaking therefrom at the operating frequency is in phase at the periphery of said plates, said plates, said disk, and said probe being substantially coaxial.
- 20 4. In an antenna, the combination of radiating means adapted to produce non-directional radiation in a plane perpendicular to a chosen axis, a disk of material refractive to electromagnetic radiation substantially coaxial with said axis and enclosing said radiating means, said disc diminishing in thickness from the center to the edge.
